[57] **CLAIM**

The ornamental design for a pedal-boat, as shown and described.

DESCRIPTION

FIG. 1 is a top right side perspective view of a pedal-boat showing my design;

FIG. 2 is a left side elevation view thereof, the other side being a mirror image of that shown;

FIG. 3 is a front end elevation view thereof;

FIG. 4 is a rear end elevation view thereof;

FIG. 5 is a top plan view thereof;

FIG. 6 is a bottom plan view thereof.
